UNITED STATES PATENT OFFICE.

HARRY L. COIT, OF BRIDGEPORT, CONNECTICUT.

CHECK PROTECTOR.

Application filed July 29, 1922. Serial No. 578,286.

To all whom it may concern:

Be it known that I, HARRY L. COIT, a citizen of the United States, residing at Bridgeport, in the county of Fairfield and State of Connecticut, have invented a new and useful Improvement in Check Protectors; and I do hereby declare the following, when taken in connection with the accompanying drawings and the characters of reference 10 marked thereon, to be a full, clear, and exact description of the same, and which said drawings constitute part of this application, and represent, in—

Fig. 1 a plan view of a check protector 15 constructed in accordance with my invention.

Fig. 2 an end view of the same.

Fig. 3 a side view, showing the protector 20 in position to act upon the face of a check, the device being shown in an exaggeratedly large scale for clearance of construction.

This invention relates to improvement in check protectors, and particularly to portable devices for this purpose, the object being 25 to produce a device which is not only of sufficient size to accomplish the desired result, but is also so small that it may be readily carried in the pocket, and the invention consists in the construction as hereinafter described and particularly recited in 30 the claims.

In carrying out my invention, I form a holder from a strip of spring metal curved at the center, forming two arms 5 and 6, the 35 ends 7 and 8 of which are bent inward to form bearings for the outer ends of studs 9 and 10, which are supported at their inner ends in the outwardly-extending fingers 11 and 12 formed at the outer end of 40 a V-shaped spring 13, the said fingers 11 and 12 being soldered, or otherwise secured, to the arms 5 and 6. Upon one of the studs 9 is a wheel 14 having two or more annular rows of points 15, and on the other stud 10 45 is a wheel 16 having transverse teeth 17

like an ordinary pinion, the two wheels being adapted to be brought closely together when the arms 5 and 6 are pressed together by the fingers. A check to be perforated is placed between the two wheels, 50 with the lower edge of the check entering between the sides of the V-shaped spring 13, so that, when the device is moved from left to right, a line of perforations will be formed parallel with the lower edge of the check, 55 and following the line on which the amount of the check is usually written. By employing the heel with the projections 15 and the wheel 16, a series of perforations are formed in the paper, rather than a mere roughening, 60 so that the paper, having once been perforated, cannot be smoothed out and the action of the protector obliterated. Furthermore, I provide a device which is of such small compass that it may be conveniently carried 65 in the pocket.

I claim:

1. A check protector comprising a pair of connecting arms having inwardly-turned ends, a V-shaped spring arranged between 70 said arms and formed at their outer ends with fingers connected with said arms, and abrading wheels mounted at the outer ends of said arms.

2. A check protector comprising a pair 75 of connecting arms having inwardly-turned ends, a V-shaped spring arranged between said arms and having outwardly-extending fingers at its outer end connected with said arms, said fingers and ends forming bearings for abrading-members, one of which is formed with outwardly-projecting teeth 80 and the other with transverse teeth.

In testimony whereof, I have signed this 85 specification in the presence of two subscribing witnesses.

HARRY L. COIT.

Witnesses:

JOHN M. HANSEN,
R. P. BROWN.
